UNITED STATES PATENT OFFICE.

JOHN B. GALLAGHER, OF BUTTE, MONTANA.

CHECK-VALVE FOR LOCOMOTIVE-BOILERS.

1,257,076.

Specification of Letters Patent. Patented Feb. 19, 1918.

Application filed May 9, 1916. Serial No. 96,379.

To all whom it may concern:

Be it known that I, JOHN B. GALLAGHER, a citizen of the United States, residing at Butte, in the county of Silverbow and State 5 of Montana, have invented a certain new and useful Check-Valve for Locomotive-Boilers, of which the following is a specification.

This invention relates, generally, to check 10 valves for steam boilers and particularly to means for operating said valves to enable the cleaning of the valve seats from foreign substances; to release said valves when under pressure in the event that they become 15 jammed; and to grind the same in the event of leakage without dismantling the valve and without blowing out the boiler, and it has for its object to provide a simple, durable, and comparatively inexpensive boiler 20 check valve, and it consists in the parts and combinations of parts hereinafter described and claimed.

In the accompanying drawings, forming a part of this specification,

25 Figure 1 is a central vertical section of a check valve showing my invention in place.

Fig. 2 is a similar section taken on line at right angles to the view shown in Fig. 1.

Fig. 3 is a section on the line 3—3 of 30 Fig. 1.

Similar letters refer to similar parts in all the views.

Referring to the drawings, A represents a 35 valve casing having a central opening B formed with screw-threads to receive the threaded cap C to close the same. At the bottom end of the opening B an internal shoulder *a* is formed to provide a seat or support for the disk D, said disk D having a 40 ground joint with the shoulder to prevent leakage. To the center of the underside of the disk D a guide pocket E is formed which extends downwardly in order to receive the stem F of the valve G and guide the same in 45 its vertical movement. The check valve G comprises the annular flange or head C' to rest on the valve seat *b* and the downwardly extending guides *d* by which it is guided in its movement. H is the branch inlet pipe 50 from the injector and K the outlet pipe from the valve casing to the boiler. The pipe K is provided with a collar or flange L, through which the valve casing is bolted to the boiler the contacting faces being ground 55 so as to prevent leakage.

The valve casing A is provided with a

downward extension L' having a smooth bored opening into the casing and an exterior threaded opening into which the end of the tubular casing M provided with a 60 smooth longitudinal bore, is screwed and through which casing a rod O extends and into the valve casing.

The head or forked end of rod O rests normally below the valve G and when the 65 valve becomes clogged or dirty it may be cleaned by raising the rod, the forked end of the latter engaging the guides *d* and the valve is lifted from its seat permitting the flow of water from the boiler to wash off the 70 valve seat. In the event of a leakage the valve may be turned or rotated on its seat and, under boiler pressure, may readily be turned or rotated by the rod and ground on the seat, thus stopping the leak. The upper 75 forked end P of the rod rests, when not in use, out of the way of the valve. At its other end the rod O carries a crank handle *h*, whereby it may be moved upwardly, and, when necessary turned or rotated. The 80 lower end of the tubular casing, M, screws into the stuffing box R. The stuffing box R comprises the nut *i*, within which a follower *m* is seated.

Having thus described my invention, what 85 I claim is:

1. A check valve for boiler feeds, comprising a casing having a central opening, a cap for removably closing the opening, an extension projecting through the opening 90 and having a guide pocket therein, a valve carrying a guiding stem normally in engagement with said pocket, an extension on said casing having a smooth bore entering into said casing, a rod having a forked end arranged in said casing and extending through the bore in said extension a stuffing box on said extension through which the rod passes, said rod adapted to slide in said bore to cause the forked end thereof to engage the valve to lift it from its seat, and means to rotate the rod when in engagement with the valve to grind the valve. 95

2. A check valve, comprising a spherical hollow body having a threaded opening in 105 the top thereof, an annular shoulder within the body forming a valve seat, tubular projections, one communicating with the interior of the body on one side of the valve seat and the other on the opposite side of said 110 valve seat, a cap for removably closing said opening, an extension projecting down-

wardly through the opening and having a guide pocket therein, a valve for said valve seat and having a guiding stem thereon extending upwardly into said guide pocket and 5 having guide fins extending downwardly therefrom and engaging the wall of the anular shoulder, a rod slidably and rotatably extended through the bottom wall of the body and having a forked inner end engageable with the guide fins of the valve, a stuffing-box carried by the body about said rod,

and a handle on the outer end of the rod, the forked end of the rod being adapted to be moved into and out of operative engagement with the fins of the valve by the sliding 15 movement of the rod.

In testimony whereof, I affix my signature, in the presence of two witnesses.

JOHN B. GALLAGHER.

Witnesses:

EDWARD NEWMAN,
F. J. POOL.
